UNITED STATES PATENT OFFICE.

JOHN THOMAS PENNY AND WILLIAM HENRY RICHARDSON, OF ADELAIDE,
SOUTH AUSTRALIA.

APPARATUS FOR TRITURATING AND AMALGAMATING AURIFEROUS AND ARGENTIFEROUS ORES.

SPECIFICATION forming part of Letters Patent No. 552,392, dated December 31, 1895.

Application filed May 9, 1895. Serial No. 548,714. (No model.)

To all whom it may concern:

Be it known that we, JOHN THOMAS PENNY, mining agent, and WILLIAM HENRY RICHARDSON, engineer, subjects of the Queen of Great Britain, residing at Grenfell Street, Adelaide, in the Province of South Australia, have invented new and useful Improvements in Apparatus for Triturating and Amalgamating Auriferous and Argentiferous Ores, of which the following is a specification.

Our invention relates to the treatment of gold and silver bearing ores which have been reduced to the consistency of pulp or slimes. The gold or silver in such ores being disseminated through them in an extremely finely-divided state it has hitherto been found practically impossible to effect, especially with certain classes of ores, such as kaolin, a separation of the metal from the gangue. We propose to accomplish this by repeated trituration under such pressure and at such high rate of speed as will develop considerable heat by friction, combining alternately with such trituration an amalgamation assisted by percussion.

The object of our invention is to provide a machine in which the ore-pulp can be repeatedly triturated to extreme fineness between plates of iron, one or both of which may be driven at a high speed under pressure, and to so arrange that, between each triturating operation, the metallic contents are amalgamated by the ore being thrown by centrifugal force from the triturating-plates against the sides of the amalgamators. We further provide a distributor and a settling-pan, in which final amalgamation takes place before the discharge of the tailings or waste.

In the accompanying drawings, illustrating our invention, Figure I is a sectional elevation of the apparatus complete; Fig. II, a plan of the feeding-hopper with supply-openings, showing radial arms for support of same; Fig. III, a plan of the carrier of the top triturating-plate. Fig. IV is a plan view of the top triturating-plate; Fig. V, a plan of the carrier of bottom triturating-plate. Fig. VI is a plan view of the bottom triturating-plate; Fig. VII, a plan of distributor; Fig. VIII, a

sectional elevation of collar on central shaft; Fig. IX, a plan of the same; Fig. X, a plan of settling or final amalgamating-pan.

Similar letters of reference indicate corresponding parts in all figures.

A is the circular casing in which the working parts are contained, and which is supported upon a solid bed or base A'; B, a central vertical shaft, the middle upper portion of which is squared for the purpose hereinafter described. The center shaft B is driven by means of gear-wheels B' B², the latter being keyed to a main driving-shaft B³, revolving in suitable bearings and provided with fast and loose pulleys B⁴ B⁵ and with a fly-wheel B⁶. The vertical shaft B is supported on a suitable end bearing C, arranged in a bar C', hinged to the base A'. The bar C' is provided with a suitable screw attachment C², by means of which it can be raised or lowered as required, and the shaft B correspondingly affected. The upper end of the shaft B revolves in a suitable bearing D fixed in the center of cross-pieces D'. The cross-pieces D' are supported by converging angle or cast-iron frames D², arranged at opposite sides outside the casing A, and having their lower ends bolted to the base A'. The casing is provided with a circular feed-hopper E, having preferably three feed-openings E'. The hopper E is supported by a cast piece having three radial arms E², Fig. II. Through the chutes E' the pulp or slimes are delivered into the machine in a continuous stream in preferably regulated quantities, the hopper E being fed from any suitable source of supply. Through the end of each of the radial arms E² a vertical bar F is passed. These vertical bars F are provided with a series of collars F', for the purpose hereinafter more particularly described, and upon back nuts, screwed upon each upper end, is placed the respective radial arm E², the whole being securely held together by means of screw-nuts F², placed at the top and bottom of the bars F.

As before described, the upper middle portion of the vertical shaft B is squared in order that there may be built upon it a series of collars, Fig. VIII, together with the carriers of

- the lower triturating-plates, Fig. V. A shoulder B^7 is formed upon the shaft B , and above it the shaft is squared as before described.
- On this shoulder is placed a circular bottom 5 plate G , and upon it a collar H , Fig. VIII, provided with a lower flange H' . The collars H are square-shaped, and are provided with a square opening, as shown in Fig. IX, of such size as to fit the square of the central shaft B .
- 10 Over the collar H which rests on the plate G is placed a second flanged collar H' . This second flanged collar is provided with an india-rubber block or other spring H^2 extending upward about half of the height of the collar.
- 15 Over the collar H , and upon the india-rubber or other spring H^2 , is placed the carrier I of the lower triturating-plate, as shown more particularly in Fig. V. This carrier I is provided with a squared central opening fitting over the 20 square of the collar H' , and the body of the plate is bent or otherwise cast in the form as shown more particularly in section in Fig. I. The carrier-plate I is provided with three or more holes I' , into which drop similar projections, cast or otherwise formed on the bottom 25 of the lower triturating-plate. The lower triturating-plate I^2 , as shown more particularly in plan in Fig. VI, is provided with a central circular opening I^3 , and with three or more 30 deep recesses I^4 radiating therefrom. The plate I^2 is provided with pins or studs I^5 cast on its lower surface in such position and of such size as to intimately engage the openings I' in the lower carrier I . Upon the upper surface 35 of this lower triturating-plate, and having its lower surface in intimate connection with it, is placed the upper triturating-plate K of the form as shown more particularly in plan in Fig. IV. The upper triturating-plate K has 40 also a central opening K' , and is provided with recesses K^2 somewhat shallower than the recesses I^4 in the lower triturating-plate I^2 . The upper triturating-plate K is also provided with suitable studs or projections K^3 , cast on its upper surface for the purpose of engaging similar 45 openings in its carrier. This carrier L is of the form as shown more particularly in plan in Fig. III. It is provided with a circular opening L' of similar size to the circular openings in the upper and lower triturating-plates K and I^2 , and with suitable holes L^2 for the 50 purpose of engaging studs K^3 in the upper triturating-plate K as before described. To the carrier L are bolted or otherwise secured three arms L^3 . These are bent upward and outward in the form as shown more particularly in Fig. I, and each outer end is provided with a suitable opening L^4 fitting over the vertical bar F as before described.
- 55 As shown in Fig. I, it will be seen that the pairs of triturating-plates are built up in series one over the other until a sufficient number have been placed upon the vertical shaft to extend upward sufficiently near the top of the machine. This building is affected by placing one above the other as before described with collar H and spring H^2 upon col-

lar and spring until the whole is complete. The screw-nuts F^2 at the top and bottom of the vertical bars F are then tightened, and the 70 whole of the radial arms L^3 of the upper carriers L become rigidly fixed. The central shaft B is then raised by means of a screw attachment C^2 and the hinged bar C' , until the lower triturating-plates I^2 are in intimate connection 75 with the upper triturating-plates K . By means of the same screw attachment the pressure of the lower upon the upper triturating-plates can be adjusted according to the class and character of ore under treatment, and whether 80 greater or less friction is required for its successful trituration.

The ore as fed from the supply-hopper passes through the feed-openings E' , and falls into a central chute M . This, as shown in section in Fig. I, is cone-shaped, and is securely fixed to and rotated by the uppermost carrier L of the series. The central chute M is provided with a circular opening of similar size to the central openings L', I^3 , and K' . Its outer 90 edges are carried upward sufficiently high to prevent the ore contents from splashing over during its revolution. The ore directed by this feed-chute M fills the circular openings in the triturating-plates, and by means of the 95 recesses I^4 and K^2 flows between them. The plates I^2 and K are in the meantime driven in opposite directions by the devices hereinafter described, at a high rate of speed, the ore being finally discharged in a continuous stream from 100 their outer edge. The trituration may be carried on by a single or double action of the plates. In a single action the lower triturating-plate I^2 only revolves, the upper triturating-plate K and the amalgamators being 105 stationary. In a double action the bottom plate is revolved at a high rate of speed, and the upper plate K and amalgamators in the opposite direction at a lower rate.

For combining amalgamation with percussion with this rapid trituration a series of circular amalgamating-pans are placed between the series of titrating devices. These amalgamating-pans N are preferably formed as shown in section in Fig. I. They are constructed with a central opening of similar dimensions to that, L' , of the upper carrier L , and being securely fixed upon it toward its center, rotate with it when in double action. It will be seen by reference to Fig. I that 110 these amalgamating-pans N are cone-shaped toward their base, and that the upper portion is dished at N' , so as to form a riffle in which mercury can be placed. The pan is then bent upward and turned inward upon itself, in 115 order to prevent the ore from being splashed over when forcibly thrown into it from between the triturating-plates. In this way the ore passing through the first titrator is thrown with force against the curved upper portion of the amalgamating-pan N . The percussion causes a portion of the metal to be 120 amalgamated, and to gradually move down with a certain amount of attrition into the 125 amalgamator.

riffle N'. The ore is carried over, down the cone-shaped base into the circular opening in next triturator of the series, to be discharged from it in a similar manner into a similar 5 amalgamating-pan, and so on alternately triturating and amalgamating with percussion until the lowest series of the amalgamating-pans is reached.

We find in actual practice that the greater 10 portion of the metallic contents of the ore is caught in its passage over the series of amalgamating-pans, as before described; but in order to extract any traces of metal which may be left, the ore is discharged from the lowest 15 amalgamating-pan N into the center of a circular distributor O made of copper, in the form as shown more particularly in Fig. VII. The center of this distributor O is prolonged upward in the form of a cone O', as shown in 20 section in Fig. I. The outer wall of the distributor O is formed of a series of upwardly-projecting plates O², the corners being left open, as shown in Fig. VII, in order to allow 25 of the passage of the stuff. The distributor O being placed upon the plate G, is revolved at a high rate of speed, so that the ore-pulp is discharged by centrifugal force through the opening as provided. It is thrown against a circular amalgamated copper shield P', provided 30 with a riffle and fixed to the lowest projecting arm L³ of the series. From the shield P' the pulp is discharged by a circular plate P into a settling-pan, where it is finally amalgamated, and the tailings and refuse discharged in a continuous stream, as hereinafter 35 described.

The triturating-plates may be provided with a single, but preferably with a double, action, as before described. The revolution of the 40 series of lower triturating-plates is accomplished, as before described, by the squared openings in the lower carriers I fitting over the squared collar H, which itself is fitted upon the shaft B, the shaft B being driven by gear-wheels B' and B² from the main shaft B³, the 45 base-plate G and the distributor O being driven in the same direction. The upper triturating-plates and amalgamating-pans when in double action are driven in the opposite direction by the lower ends of the rods F being passed through the radial arms Q' cast upon a crown gear-wheel Q driven by a beveled wheel Q secured to the main driving-shaft B³.

50 After passing through the machine the ore-pulp is delivered from the discharge-plate P into a circular settling-pan or race R, formed of copper and having vertical divisions R', as shown in plan in Fig. X and in section in 55 Fig. I. The settling-pan or race R is supported in any suitable manner from the base d' and is intended to be stationary. The walls R' formed in the race R by the vertical divisions R' are amalgamated and the bottom of the wells supplied with mercury. The ore-pulp, being discharged into the innermost well R², travels in the direction of the arrows, as

shown, and to be finally discharged from the discharge-chute R³, the flow being assisted in its progress by a series of vibrating rakes S. 70 The series of rakes S are suspended from a frame S', the ends of which are bolted to a circular plate S², which sits loosely upon collar Q⁴ placed upon the central shaft B. Motion is imparted to the rakes S by a crank attachment S³ loosely attached by means of a screw-bolt to a toothed wheel S⁴. The toothed wheel S⁴ is driven by a small toothed wheel S⁵, secured to the main driving-shaft B³. By means of this vibrating motion of the rakes S the ore is slowly kept in suspension and flows forward in the settling-pan or race R in the direction of the arrows, as before described, the heavier particles being allowed to settle and any metal contained therein being 85 finally amalgamated. The concentrates and amalgam are drawn from an outlet provided for the purpose, the light stuff or tailings being carried over the discharge. 90

In the treatment of certain classes of ore it may be necessary to add certain chemicals in order to assist in the extraction of the metallic contents. This should be done prior to the ore being introduced into our machine for trituration, but such addition forms no 95 part of our invention.

We are aware that the trituration and subsequent amalgamation of finely-divided ores is not new, such treatment being the object of our former invention, for which we have obtained United States of America Letters Patent No. 445,300; also, that ore has been previously ground between circular mullers and discharged into an outer annular amalgamating well or pan, but our invention, as before described, differs essentially from these former inventions, both in purpose and construction, in the following respects: The purpose of such grinding is a further reduction of coarse ore. Our machine receives the ore after such further reduction, for a trituration to impalpable fineness, involving a considerable amount of friction, and consequently increase of temperature. Such trituration is caused to alternate with an amalgamation 105 with percussion. The ore pulp is triturated and amalgamated under percussion in a rotating amalgamator, alternately again and again, until it has passed through the machine. Such amalgamation is accompanied by sharp 110 percussion of the ore against the walls of the amalgamating-pan, causing the metals to be separated from the gangue, and the amalgamation to be materially assisted. The alternate trituration and amalgamation 115 is combined with the final amalgamation with percussion by means of a distributor, and a further amalgamation in a settling-pan before 120 final discharge of the tailings.

Having now particularly described and ascertained the nature of our said invention and in what manner the same is to be performed, we declare that what we claim is—

1. In combination with the series of plates

arranged in pairs with means for revolving the plates of each pair in opposite directions, means for feeding the ore between the upper pair of plates at the center, and an annular 5 pan having a raised wall surrounding each pair of plates to catch the material thrown therefrom, said pan having an annular amalgamating channel and a funnel shaped bottom for conveying the material to the central 10 portion of the next pair of plates, substantially as described.

2. In combination with the series of plates arranged in pairs and revolving in opposite directions, the amalgamating pans arranged 15 to receive the ore from one pair of plates and convey it to the next, the distributor plate O having a conical center and a perforated outer wall, and an annular shield surrounding said outer wall and arranged to receive the material 20 thrown therefrom, substantially as described.

3. In combination with the triturating plates, and amalgamating pans, the station-

ary settling pan having a series of annular partitions forming zigzag passageways, the 25 rocking bar having rakes carried on opposite ends thereof with fingers depending into the passageways, and means for rocking said bar, substantially as described.

4. In combination, the central shaft, the 30 series of triturating plates carried thereby, the top and bottom radial arms journaled on the shaft, the vertical rods connecting said radial arms, the second set of triturating plates supported from the vertical rods, 35 means for rotating the central shaft in one direction and means for rotating the radial arms and rods in the opposite, substantially as described.

In witness whereof we have hereunto set 40 our hands in presence of two witnesses.

JOHN THOMAS PENNY.

WILLIAM HENRY RICHARDSON.
